UNITED STATES PATENT OFFICE.

JOHN RICHARDS, OF SAN FRANCISCO, CALIFORNIA, ASSIGNOR TO TURBINE PUMP COMPANY, OF JERSEY CITY, NEW JERSEY, A CORPORATION OF NEW JERSEY.

TURBINE-PUMP.

1,112,560.

Specification of Letters Patent.

Patented Oct. 6, 1914.

Application filed October 17, 1901. Serial No. 78,925.

To all whom it may concern:

Be it known that I, JOHN RICHARDS, a citizen of the United States, residing in the city and county of San Francisco and State 5 of California, has invented certain new and useful Improvements in Turbine-Pumps; and I do hereby declare the following to be a full, clear, and exact description of the same, reference being had to the accompanying drawings, forming a part of this 10 specification.

My invention relates to rotary pumps of the turbine type and to certain improvements in these as hereinafter described and 15 illustrated in drawings that form a part of this specification.

The objects of my invention are to attain an organized construction of such pumps, when compound or multiple acting—to vary 20 the pressure produced without changing the speed of rotation—to maintain continuous rotation of the water in the pump, and in various constructive features hereinafter particularly pointed out by the aid of the 25 drawings in which:

Figure I is a side elevation, partially in section, of a turbine pump embodying my improvements—Fig. II an end view of the main frame and side view of the discharge 30 impeller chamber looking as indicated by the arrow at *e* in Fig I—Fig. III is a section showing the shape of the vanes on the lines *a—a* in Fig. I that direct the water in its passage from one impeller to the next—35 Fig. IV is an enlarged section taken transversely through the discharge chamber, Fig. I, showing the means for reducing the diameter of the discharge chamber, and showing *in situ* a portion of a throat ring 40 modified to accommodate an impeller of reduced diameter. Fig. V is a similar transverse section to Fig. IV, showing the means for reducing the diameter of the discharge chamber with the ordinary throat ring *in 45 situ*. Fig. VI is a transverse section of a portion of the discharge chamber and impeller when the latter discharges diametrically into the former instead of tangentially.

The supporting frame 1 is of the usual 50 construction arranged to receive the required number of impeller chambers 2, 3 and 4 that have therein the impellers 5 of like construction, provided with internal vanes 8, 9 and 10, the latter connecting to the nave 55 as shown in Fig. II, and external vanes 12

that span or fill laterally the chambers in which the impellers revolve. The discharge chamber of the main casing 4 is annular, the annulus being substantially circular in cross section, as shown in Figs. I, IV, V, 60 and VI. In Figs. I, IV and V said circular cross-section is modified to admit of an arrangement of the impeller whereby it discharges tangentially into said chamber instead of directly, as in Fig. VI. The area 65 of the annular discharge chamber is thus encroached upon to admit the wall 28, but by this modification the water is discharged into the chamber with less agitation than when the throat-way is central, as in Fig. 70 VI, and the diminished area is compensated for, while a discharge chamber of reduced diameter can be used with an impeller of full diameter with equal efficiency. The amount of comparative reduction in diameter 75 is shown by comparing line A, Fig. V, with line B, Fig. VI.

The impellers 5 are all keyed to the spindle 13, and are held against lateral movement by means of the screw collar or 80 nut 14 and the inclosed distance collars 15, that fill between the vanes of the impellers, also forming in part bearings for the spindle 13 in the walls 7 between the impellers 5. On these walls 7 are formed the nipples 85 11 that complete a smooth curved course for the water as it approaches and enters the nozzles of the impellers 5. Besides these collars 15, the spindle 13 has bearings in the gland 17, the shell 18, on the nipples 19 90 of the impellers 5, in the gland 20 and in the rear bearing 22, the whole amounting in length to half that of the spindle 13. Of these bearings the main ones, 17 and 22, are not exposed to the water and can be lubricated from the cups 23 and 24, as shown in Fig. I. The pump casing consists of the separable chambers 2, 3 and 4 and end covering plate 25. The chambers 2, 3 and 4 are preferably made separable and held together by the screw bolts 26 that pass loosely through the sleeves or lugs 27 and are screwed into bosses 16 on the side of the chamber 4 so their clamping strain will not cause distortion of this latter or of the web 105 plate 28. This web plate 28, forming an inner wall of the discharge chamber, provides for the tangential inlet to the discharge chamber heretofore described.

Surrounding the impellers 5 are narrow 110

throat rings 30 having a series of acute pointed vanes 29 that direct the water outward or away from the impellers 5 and prevent back-flow. To explain this action let it be supposed that the velocity of the impellers be eighty feet a second at their periphery and that the vanes in the impeller and also the vanes on the throat ring to be thirty in number, then the stream of water will be cut by these vanes a large number of times each second of time, receiving as many impulses and producing nearly positive impulsion of the water.

In operating, water enters through the suction pipe 31, passes through the pump in the direction indicated by arrows in Fig. I through passages of nearly uniform area in cross section, in easy curves producing a sigmoidal course from the inlet at 32 to the discharge chamber 37 and out at the discharge nozzle 34. In this manner the water continues in revolution after entering at 32, through the impellers 5, in the curved passages 35 following the vanes 36, shown in section in Fig. III from the periphery to the center and one impeller to the next and to the discharge chamber 37 until it meets the diverting wall or diaphragm 28 which deflects the water by an easy curve to the discharge nozzle 34.

When a pump of this type has to be driven at a fixed rate of revolution as in the case of being directly connected to an electric motor, the diameters of the impellers 5 have to be accurately adjusted to suit the head or resistance and the quantity of water to be discharged. This I provide for by inserting around one or more of the impellers 5, removable rings as shown in Fig. IV where 40 5 is a broken section of one of the impellers reduced in diameter to receive the throat ring as shown in section above it. The portions 30 and 29 of this ring corresponds in general to the throat rings 30 in Figs. I and II except that the ledges 42 are added to fill off the side chambers in which the vanes 12 revolve and an extension 41 is provided to fill the side of the throat above the part 30. This device when applied reduces the 45 effective diameter of the impeller twice as much as the depth of the part 40, the vanes 29 corresponding to those with like reference in Fig. II, except being longer. Such supplementary throat rings can be applied 50 around one or all of the impellers 5 and permits a ready means of adjustment in case the speed and volume is too great for an intended service.

As the main or discharge chamber 4 sustains the sum of the pressures produced in all the impellers this chamber is not made open on the outside, but is provided with double walls 43—44 with a number of ribs 45 between these walls to stiffen them, the 65 outer wall 43 being arranged to receive the

sleeve 46 which contains the packing gland 20 to prevent the escape of water, the bearing 22 not exposed to the water, a thrust bearing 47, and a removable case 48 to contain oil for the purpose of lubricating the thrust bearing 47 and the bearing 22. A sleeve similar to the one 46 can be applied at the other end of the spindle instead of the gland bearing 17 and shell bearing 18, and is preferable when the length or projection of the parts is not objectionable.

It will be understood that the number of impellers employed depends on the speed and pressure to be produced, and that these and the chambers 2 and 3 being uniform any number can be employed.

Having described the nature and objects of my invention and manner of its operation, what I claim as new and desire to secure by letters patent is:

1. In a rotary pump, an inlet way, an annular discharge chamber whose discharge annulus is approximately circular in cross section, one or more connected impeller chambers between said inlet way and said discharge chamber, and an annular throat way between the adjacent impeller chamber and said discharge annulus, within the boundary of the circular section of the latter, tangential to the inner wall thereof, approximately opposite to the central line of said annulus, forming a continuous communication between said impeller chamber and said discharge annulus, and the adjacent impeller chamber, tangential to the ring section of the said discharge chamber, substantially as specified.

2. In a rotary pump, an annular discharge chamber, the annulus being approximately circular in cross section, an annular throat way within the boundary of the circular section, tangential to the inner wall of said discharge annulus, approximately opposite to the central line of the annulus, an impeller chamber communicating with said throat way, an impeller therein, and a partition within the area of the circular section separating said impeller chamber from said discharge annulus up to the junction of the latter with the annular throatway, substantially as specified.

3. In a rotary pump, the discharge chamber 4 provided with the walls or webs 43 and 44, the former adapted to receive a support for the pump spindle and the latter forming in part one wall of the adjoining impeller chamber, and ribs 45 between these walls to brace them.

4. In a rotary pump, a series of similar impeller chambers detachably connected together, rotary impellers in said chambers, water passages alternating with the impellers, curved annular passages external to and leading from the impellers to said water passages, and nipples 11 that form with the

- impeller inlets curved annular passages from the said water passages to each next impeller in the series, substantially as specified.
5. In a rotary pump, a series of impeller chambers detachably connected together, a central impeller spindle, a series of impellers in said chambers secured on said spindle, a chambered sleeve 46, supporting the lateral one end, and having gland 20 for excluding water, oil-bearing 22, thrust bearing 47, beyond chambered sleeve 46 and removable oil case 48, substantially as specified.
6. In a rotary pump, an annular discharge chamber, a central impeller spindle therethrough, flanged hollow sleeve 46 secured to said discharge chamber, packing gland 20 in said hollow sleeve, oil bearing 22, on outer extremity of sleeve 46, thrust bearing 47, external to oil bearing 22, and removable oil chamber 48, inclosing thrust bearing 47, substantially as specified.
7. In a rotary pump, an impeller chamber, a rotary impeller therein, a discharge way from said impeller chamber, an annular recess between said impeller and said discharge way, exchangeable throat rings 30 of different sizes corresponding to impellers of different diameters, said rings provided with vanes 29, extension 41, and ledges 42, to fill the variable spaces in said annular recess when a throat ring of fitting size is inserted, substantially as specified.
8. In a rotary pump, a series of impeller chambers detachably connected together, rotary impellers in said chambers, water passages alternating with the impellers, having vanes between which are return passages from one impeller to the next in the series, curved annular passages external to and leading from the impellers to said return passages, and means forming with the impeller inlets curved annular passages from the said return passages to each next impeller in the series.
9. In a rotary pump, a series of similar impeller chambers detachably connected together, rotary impellers in said chambers, water passages alternating with the impellers and having vanes providing return passages, curved annular passages leading from the impellers to said return passages,
- throat rings surrounding the impellers and having a series of vanes that direct the water outward or away from the impellers, said 55 throat ring forming a part of the curved passages leading from the impellers to the return passages, and means forming curved annular passages from the said spiral passages to each next impeller in the series. 60
10. In a rotary pump, a series of impeller chambers, rotary impellers in said chambers provided with radial discharge passages, throat rings surrounding the impellers and having a series of vanes that direct the water outward and away from the impellers and prevent back flow, return passages adjacent to the impellers, each return passage connecting by a curved way with the next succeeding impeller, fixed vanes in said return 70 passages, and curved annular passages external to said impellers and return passages forming communication from each impeller at its periphery to each return passage.
11. In a rotary pump, a series of impeller 75 chambers, rotary impellers in said chambers provided with radial discharge passages, throat rings surrounding the impellers, return passages adjacent to the impellers, each return passage connecting by a curved way 80 with the next succeeding impeller, means forming said curved way, fixed vanes in said return passages, and curved annular passages external to said impellers and forming communication through the throat ring 85 from each impeller at its periphery to each return passage.
12. The combination with an impeller casing and its impeller chamber and throat way, of a throat ring having vanes, said 90 throat ring being formed with a narrow portion of such width as to fit the throat way and a wider portion of such width as to fill the impeller chamber between the impeller and throat way, whereby an impeller of less 95 diameter than the impeller chamber of the casing may be used.

In testimony whereof I have signed my name to this specification in the presence of two subscribing witnesses.

JOHN RICHARDS.
